UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

AUTOMATIC MACHINE FOR LEVELING PRINTING CHARACTERS.

1,239,678.

Specification of Letters Patent. Patented Sept. 11, 1917.

Application filed August 7, 1916. Serial No. 113,664.

To all whom it may concern:

Be it known that I, JOSEPH S. DUNCAN, a citizen of the United States, residing at Chicago, in the county of Cook and State 5 of Illinois, have invented certain new and useful Improvements in Automatic Machines for Leveling Printing Characters, of which the following is a specification.

This invention relates to an automatic 10 machine for leveling the faces of printing characters struck up from the body of printing plates.

Prior to my present invention printing characters have been formed on metal blanks 15 by striking up characters from the body of the blank. Numerous machines equipped with coöperating punches and dies have been devised for this purpose. The faces of the printing characters when so formed are more 20 or less curved, particularly adjacent the edges, so that difficulty is experienced in obtaining sharply defined impressions from the plates. Furthermore, certain characters will, owing to slight inaccuracies of the 25 punches and dies and the operating mechanism therefor, be higher than others so that the faces of the characters are not in exactly the same plane.

It is an object of my invention to provide 30 means to correct this difficulty by bringing the faces of all of the characters in the same plane and flattening the faces to produce sharply defined edges thereon with the resulting improvement of the printing quality 35 of the plates.

A further object of my invention is the provision of an automatic attachment for a machine for making printing plates whereby printing plates of the desired character 40 may be rapidly produced.

Further objects and advantages of my invention will be apparent as it is better understood by reference to the following specification when read in connection with 45 the accompanying drawing, illustrating the preferred embodiment thereof, in which—

Figure 1 is an end elevation of a machine for making printing plates with my attachment applied thereto;

50 Fig. 2 is a front elevation of a portion of a machine for making printing plates with my attachment applied thereto, parts

being broken away for purposes of better illustration;

Fig. 3 is a rear elevation of the structure 55 illustrated in Fig. 2;

Fig. 4 is a horizontal section on the line 4—4 of Fig. 2;

Fig. 5 is a detail in elevation with parts in section illustrating the automatic controlling mechanism; and

Fig. 6 is a horizontal section on the line 6—6 of Fig. 2.

Referring to the drawing I have illustrated a machine for making printing plates 65 known as the "graphotype" and comprising a frame 1, a pair of rotatable heads 2 and 3 bearing coöperating dies 4 and punches 5 adapted to be moved to position to strike up a printing character from the body of a 70 plate 6 which is held in a jaw 7 mounted on a carriage 8. The carriage 8 is supported by rollers 9 and 10 on a guide 11 and is movable transversely of the machine to successively position different portions of 75 the plate 6 between the punch 4 and the die 5. The jaw 7 is movable transversely of the carriage 8 to produce the separate lines of printing characters. The carriage 8 is connected by a flexible band to a spring- 80

controlled drum 13 which biases the carriage 8 to the right, viewing Fig. 2, and a suitable escapement (not shown) is provided which permits the carriage 8 to move a distance equal to the width of a character 85 and the necessary space between the characters after each individual character has been formed. When the last character has been formed the carriage 8 is released and is moved by the spring-controlled drum 13 to 90 the extreme right, viewing Fig. 2. The foregoing structure is well-known in the art and is, therefore, not described in detail, it being understood that the machine disclosed 95 is illustrative merely and that my invention may be applied to other types of machines for making printing plates to which it may be adapted.

Secured to the frame 1 of the machine for making printing plates is a frame 14 provided with a bed 15 disposed in alinement and in the same plane with the support 16 along which the plate 6 is moved during the operation of striking up the printing char- 100

acters from the body thereof. As will be readily understood when the carriage 8 is moved to the extreme right the plate 6 will be disposed above the plate 15. The upper 5 portion of the frame 14 is provided with a plate 17 rabbeted at 18 along its upper longitudinal edge to provide a guide groove. A carriage comprising a frame 19 having pins 20 thereon engaging the guide groove 10 on the plate 17 is provided with anti-friction rollers 21 and 22 mounted on shafts 23 and 24 and engaging the under surface of the plate 17. The frame 19 is pivotally mounted on a shaft 23 which is supported in 15 a member 25 pivotally connected to a lever 27. A spring 28 is disposed between the member 25 and a yoke 29' (Fig. 4) on the frame 19, the purpose of the spring 28 being to maintain the roller 22 in engagement 20 with the under face of the plate 17. A pressure roller 29 is rotatably mounted on a shaft 30 extending through the frame 19 and engages the roller 22 and a plate 6 disposed upon the bed 15. When the carriage is 25 moved along the bed 15 the plate 6 will be subjected to pressure by the pressure roller 29 to reduce the faces of the characters to a common plane and provide them with clearly defined edges.

30 To actuate the carriage whereby the pressure roller 29 is moved along the bed 15 I provide the main shaft 30 of the machine with teeth 31 (Fig. 4) meshing with a gear 32 having a crank pin 33 thereon. A link 35 connects the crank pin 33 to the free end of the arm 35 loosely mounted on a shaft 36 (Fig. 1) supported in suitable bearings in an extension 37 of the frame 14. An arm 38 is secured to the shaft 36 adjacent the 40 arm 35 and is connected thereto by a spring 39 secured to pins 40 and 41 on the arms 35 and 38. An arm 42 is secured to the shaft 36 and connected to the arm 38 by a web 43. The arm 42 is provided with wear 45 plates 44 and 45 on either face thereof, the plate 45 being adapted to normally engage a stop 46 adjustably mounted in a lug 47 on the frame 14.

50 The lever 27, previously described, is loosely mounted on the shaft 36 and is provided with a dog 48 pivotally mounted at 49' thereon and biased to the position indicated in Fig. 3 by a spring 49 secured to a pin 50 on the dog 48 and to a pin 51 on the lever 27. Inasmuch as the shaft 30 is constantly rotated from a suitable source of power the arms 35 and 38, and consequently the shaft 36, will be constantly rocked. The arm 42, being secured to the shaft 36, will 55 also be rocked and when the end of the dog 48 is in engagement with the wear plate 44 on the arm 42 the lever 27 will be rocked to move the carriage bearing the pressure roller 29 along the bed 15 in the direction indicated by the arrow in Fig. 2. The car-

riage will be returned to its normal position by engagement of the arm 35 with the arm 38 upon reversal of the movement of the former. Should any obstruction be encountered by pressure roller 29 the spring 39 70 allows the arm 35 to move to the right, viewing Fig. 3, while the remaining parts are stationary, thus constituting a safety device to prevent breakage of the mechanism.

As it is only necessary to move the roller 75 29 along the bed 15 when a plate 6 is disposed thereon I provide means for normally holding the end of the dog 48 out of the path of the wear plate 44 on the arm 42 and for releasing the dog when the plate carriage 8 has disposed the plate 6 upon the bed 15. The dog 48 is provided with a pin 52 projecting therefrom and adapted to rest upon an abutment 53 on a latch 54 pivotally mounted at 55 on the frame 14. The latch 80 54 is provided with a projection 56 disposed in the path of a dog 57 pivotally mounted at 58 on the rocker 59 mounted to swing on a pivot 60 on the frame 14. The dog 57 is provided with a pin 61 projecting 85 through an opening 62 in the rocker 59, the pin 61 being connected by a spring 63' to a pin 64' on the rocker 59. A spring 63 connects the pin 64' to a pin 64 on the frame 14. The latch 54 is biased toward the position indicated by dotted lines in Fig. 5 by a spring 65 connected to a pin 66 on the latch 54 and to the pin 64 on the frame 14. Movement of the rocker 59 is limited by a pin 67 on the frame 14 projecting into an 90 opening 68 in the rocker 59, the pin 67 also serving as a stop to limit the movement of the latch 54 to the left, viewing Fig. 5.

A pin 69 on the rocker 59 projects into the path of an abutment 70 on the plate carriage 8 and consequently when the plate carriage 8 is moved to the extreme right, viewing Fig. 2, to dispose a plate 6 upon the bed 15 the rocker 59 will be turned about its pivot 60, carrying the nose of the dog 57 105 into engagement with the projection 56, whereby the latch 54 is rocked on its pivot 55 to move the abutment 53 from beneath the pin 52 and allowing the end of the dog 48 to drop into the path of the wear plate 44 on 110 the arm 42. The carriage bearing the roller 29 will be immediately moved in the direction indicated by the arrow in Fig. 2 and returned to its normal position, subjecting the plate 6 to pressure by the pressure 115 roller 29.

The dog 48 moves with the lever 27 and consequently the pin 52 is carried away from the latch 54 during the forward movement of the carriage, allowing the spring 65 to 120 draw the latch 54 to the position indicated in dotted lines in Fig. 5. When the carriage, bearing the pressure roller 29, returns to normal position the pin 52 rides onto the abutment 48 carrying the latch 54 to the full 125 130

line position in Fig. 5, whereby the latch 48 is lifted so that its end is no longer in the path of movement of the wear plate 44 on the arm 42. The cycle of operations is then 5 complete until another plate 6 is disposed upon the bed 15.

From the foregoing description it will be readily understood that I have perfected a machine which is automatically operative to 10 subject the faces of characters on a printing plate to pressure whereby the faces are reduced to a common plane and provided with sharply defined edges. My machine is simple in construction and mode of operation 15 and performs its desired function with great rapidity whereby the production of printing plates of the desired character is greatly facilitated.

It will be apparent that various changes 20 may be made in the form, construction and arrangement of the parts without departing from the spirit and scope of the invention or sacrificing any of the material advantages thereof, the form hereinbefore described being merely a preferred embodiment thereof.

I claim:

1. In a machine of the character described, 30 the combination of a movable carriage having means thereon to hold a printing plate, a bed adapted to support said plate, pressure means associated with said bed and spaced therefrom a distance equal to the desired height of the printing characters on 35 said plate, and means for automatically actuating said pressure means when a plate is disposed on said bed to reduce the faces of the printing characters to a common plane.

2. In a machine of the character described, 40 the combination of a movable carriage having means thereon to hold a printing plate, a bed adapted to support said plate, pressure means associated with said bed and spaced therefrom a distance equal to the desired 45 height of the printing characters on said plate, means for automatically actuating said pressure means when a plate is disposed on said bed to reduce the faces of the printing characters to a common plane, and 50 means permitting said pressure means to remain inoperative when an obstruction is encountered thereby while said actuating means continues to operate.

3. In a machine of the character described, 55 the combination of a movable carriage having means thereon to hold a printing plate, a bed adapted to support said plate, a pressure roller associated with said bed and spaced therefrom a distance equal to the desired 60 height of the printing characters on said plate, and means controlled by said carriage for automatically actuating said pressure roller when a plate is disposed on said bed to reduce the faces of the printing characters to a common plane.

4. In a machine of the character described, the combination of a movable carriage having means thereon to hold a printing plate, a bed adapted to support said plate, a pressure roller associated with said bed and spaced therefrom a distance equal to the desired height of the printing characters on said plate, means controlled by said carriage for automatically actuating said pressure roller when a plate is disposed on said bed 70 to reduce the faces of the printing characters to a common plane, and means permitting said pressure roller to remain inoperative when an obstruction is encountered thereby while said actuating means continues in operation.

5. In a machine of the character described, the combination of a movable carriage having means thereon to hold a printing plate, a bed adapted to support said plate, a pressure roller associated with said bed and spaced therefrom a distance equal to the desired height of the printing characters on said plate, and means for automatically actuating said pressure roller when a plate is 80 disposed on said bed including a constantly driven member, driving mechanism therefor, means normally disengaged from said member and connected to said roller, and means for causing engagement of said last-mentioned means with said member.

6. In a machine of the character described, the combination of a movable carriage having means thereon to hold a printing plate, a bed adapted to support said plate, a pressure roller associated with said bed and spaced therefrom a distance equal to the desired height of the printing characters on said plate, and means for automatically actuating said pressure roller when a plate is 90 disposed on said bed including a constantly driven member, driving mechanism therefor, means normally disengaged from said member and connected to said roller, and a trip controlled by said carriage for causing engagement of said last-mentioned means with 95 said member.

7. In a machine of the character described, the combination of a movable carriage having means thereon to hold a printing plate, a bed adapted to support said plate, a pressure roller associated with said bed and spaced therefrom a distance equal to the desired height of the printing characters on said plate, and means for automatically actuating 115 said pressure roller when a plate is disposed on said bed, including a constantly driven member, driving mechanism therefor, means normally disengaged from said member and connected to said roller, a trip controlled by said carriage for causing engagement of said last-mentioned means with said member, and a resilient connection between said constantly driven member and the driving mechanism therefor, whereby said pressure 120 roller is automatically actuated when a plate is disposed on said bed. 125

- 4
- roller is permitted to remain inactive when an obstruction is encountered thereby while said driving mechanism continues in operation.
- 5 8. In a machine of the character described, the combination of a movable carriage having means thereon to hold a printing plate, a bed adapted to support said plate, a pressure roller associated with said bed and spaced therefrom a distance equal to the desired height of the printing characters on said plate, and means for automatically actuating said pressure roller when a plate is disposed on said bed, including a constantly 10 actuated pivoted arm, a lever connected to said pressure roller and normally disengaged from said pivoted arm, and means controlled by said carriage for causing operative engagement of said lever and arm.
- 15 9. In a machine of the character described, the combination of a movable carriage having means thereon to hold a printing plate, a bed adapted to support said plate, a pressure roller associated with said bed and spaced 20 therefrom a distance equal to the desired height of the printing characters on said plate, and means for automatically actuating said pressure roller when a plate is disposed on said bed, including a constantly 25 actuated pivoted arm provided with an abutment, a latch normally holding said dog from engagement with said abutment, and means controlled by said carriage for releasing said dog, said latch being arranged to automatically engage said dog at the conclusion of each cycle of operations.
- 30

ment, a pivoted lever connected to said pressure roller, a dog on said lever, means for normally holding said dog out of the path of said abutment, and means controlled by said carriage for releasing said dog

35

10. In a machine of the character described, the combination of a movable carriage having means thereon to hold a printing plate, a bed adapted to support said plate, a pressure roller associated with said bed and spaced therefrom a distance equal to the desired height of the printing characters on said plate, and means for automatically actuating said pressure roller when a plate is disposed on said bed, including a constantly 40 actuated pivoted arm provided with an abutment, a latch normally holding said dog from engagement with said abutment, and means controlled by said carriage for releasing said dog, said latch being arranged to automatically engage said dog at the conclusion of each cycle of operations.
